UNITED STATES PATENT OFFICE.

ANDREW J. CARMICHAEL AND ORESTE BALZANO, OF NEW HAVEN, CONNECTICUT,
ASSIGNORS TO THE GREIST MANUFACTURING COMPANY, A CORPORATION OF
CONNECTICUT.

SEWING-MACHINE RUFFLER.

Application filed September 27, 1927. Serial No. 222,345.

This invention relates to that class of sewing machine ruffling attachments in which the ruffling blade is actuated from an operating lever forked for engagement with a pin or stud on the needle bar of a sewing machine, and the invention has for its object to provide a convenient regulating construction whereby the throw of the ruffling blade may be varied, as may be desired, or may 5 be rendered inoperative when it is desired to do plain sewing. The invention as herein illustrated is shown as being applied to a sewing machine ruffler which, excepting for the regulating means, is essentially the same 10 as the ruffler of the Greist patent No. 665,519, January 8, 1901.

In the accompanying drawing Figs. 1 and 2 are opposite side views of the improved ruffler, Fig. 3 is a plan view thereof, Fig. 4 20 an end view looking from the right of Figs. 1 and 3, Fig. 5 is a detail view of the operating lever, and Fig. 6 a detail view of the pendulous lever.

Referring to the drawing, 12 denotes an 25 upright portion of the frame, affording a standard, and said frame also comprises a presser foot portion 13 having a forked upper part 14 adapted for attachment to the presser bar of a sewing machine. Pivoted 30 to the standard 12 is an operating lever 15 forked for engagement with a pin or stud carried by the needle bar of a sewing machine, and also pivoted to said standard is a pendulous arm or lever 16 having a jointed 35 connection with a slide 17 carrying the ruffling blade 18.

Removably attached to the standard 12, by a screw 19, is a holder 20 to which is attached the separator plate 21, said holder 40 having a slotted portion 22 serving as a guide for the strip to be ruffled. Attached to the presser foot portion 13 of the frame is a slotted edge guide 23.

All of the parts thus far described are or 45 may be essentially the same as the ruffler of said Greist patent No. 665,519, excepting that the operating lever 15 and the pendulous lever 16 have been changed somewhat to accommodate the improved regulating means.

In the present improved ruffler the throw of the ruffling blade is varied by means of an adjusting or regulating lever 24 pivoted

to a forwardly extending offset portion of a 55 depending part 25 of the operating lever 15, said depending part of said operating lever having a slot 26 through which passes a pin 27 secured to an offset portion 24^a of said regulating lever. The pendulous arm or lever 16 is constructed with a downwardly 60 tapering opening 16^a the opposite walls of which serve as contacts for the said pin. By varying the position of the said regulating lever the pin 27 may be raised or lowered in the said opening in the pendulous lever so 65 as to bring it nearer to or farther from the center of movement of the operating lever and also of said pendulous lever, and also so as to bring it into a wider or narrower portion of the said opening in the pendulous 70 lever, thereby affording more or less lost motion between the operating lever 15 and the pendulous lever 16 from which latter the ruffling blade is reciprocated, so as to vary the throw of the said ruffling blade. The 75 levers 15 and 16 are both pivoted on the rivet 15^a so as to have the same center of movement.

The regulating lever is provided with a struck-up lug 28 adapted for engagement 80 with a series of notches 29 on the operating lever 15, so that said regulating lever may be secured in any desired position of adjustment relative to said operating lever. Said regulating lever is of thin spring steel 85 so that said lug may be readily engaged with or disengaged from said notches. The said operating lever is preferably provided with a scale 30 comprising a series of numbers for the different notches, for convenience in determining any desired position of the regulating lever.

When the regulating lever is in the position shown in full lines in Fig. 1 of the drawing the ruffling blade will be given its greatest throw, the pin 27, fixed to said regulating lever, being by this time in the narrowest part of the opening 16^a in the pendulous lever 16 and farthest from the center of motion of the operating and pendulous levers. 95 If, however, the said regulating lever be moved to the position indicated by dotted lines in Fig. 1 the pin on said regulating lever will occupy a position so near to the center of motion of the said levers and into 100 the widest portion of the opening in the

said pendulous lever that the lost motion between the said operating lever and the said pendulous lever will be so great that no movement at all will be given to the ruffling 5 blade, which may thus be very easily thrown out of action when plain sewing is to be done.

From the foregoing it will be understood that the present improvement comprises 10 simple means for regulating the throw of the ruffling blade of a sewing machine ruffler, said regulating or adjusting means being simpler and less expensive in construction than the regulating or adjusting means here- 15 tofore employed in the particular class of rufflers to which the present invention is shown as being applied.

Having thus described our invention we claim and desire to secure by Letters Patent: 20 1. In a sewing machine ruffler, the combination with a frame portion having a standard, of an operating lever pivotally mounted on said standard and having a depending portion provided with a forwardly extending offset part and a slot, a pendulous arm or lever also pivotally mounted on said standard and constructed with a downwardly tapering opening, a ruffling blade carrier jointed to the lower end of said pendulous 25 arm or lever, a ruffling blade fixed to said carrier, a regulating lever pivoted to said forwardly extending offset portion of said operating lever and having in turn an offset portion, a pin fixed to said offset portion of 30 said regulating lever and extending through 35

said slot into the said opening in the pendulous lever, and means for securing the said regulating lever in any desired position of adjustment relative to said operating lever.

2. In a sewing machine ruffler, the combination with a frame portion having a standard, of an operating lever pivotally mounted on said standard and having a depending portion provided with a forwardly extending offset part and a slot, a pendulous arm 40 or lever also pivotally mounted on said standard and constructed with a downwardly tapering opening, a ruffling blade carrier jointed to the lower end of said pendulous 45 lever or arm, a ruffling blade fixed to said carrier, a regulating lever pivoted to said forwardly extending offset portion of said operating lever and having in turn an offset portion, a pin fixed to said offset portion of 50 said regulating lever and extending through 55 said slot into the said opening in the pendulous lever, and means for securing the said regulating lever in any desired position of adjustment relative to said operating lever, said securing means consisting of a series of 60 notches on said operating lever and a struck-out stud or lug on said regulating lever, the latter being of thin spring metal affording a convenient engagement and disengagement 65 of said stud or lug and said notches.

In testimony whereof we affix our signatures.

ANDREW J. CARMICHAEL.
ORESTE BALZANO.
